UNITED STATES PATENT OFFICE.

FRANCIS H. WITTSTEIN, OF NEWARK, NEW JERSEY.

DESIGN FOR A FINGER RING.

Application filed December 11, 1923. Serial No. 7,995. Term of patent $3\frac{1}{2}$ years.

To all whom it may concern:

Be it known that I, FRANCIS H. WITTSTEIN, a citizen of the United States, and a resident of Newark, in the county of Essex and State of New Jersey, have invented a new, original, and ornamental Design for a Finger Ring, of which the following is a specification, reference being had to the accompanying drawing, forming a part thereof, wherein—

The essentials of the design consists of a grouping of symbols comprising a shield in form of a conventionalized acorn upon which appears a conventionalized repre-

sentation of a carnation emanating from the representation of a star and embraced by conventionalized laurel sprays also emanating from the representation of the star, symbolizing as a whole motherhood.

The figure is a top plan view of a finger ring showing my new design.

What I claim, and desire to secure by Letters Patent, is:

The ornamental design for a finger ring, as shown and described.

FRANCIS H. WITTSTEIN.

Witness.

S. O. COEYMAN,
